United States Patent Office

Des. 207,543
Patented May 2, 1967

207,543
CASSEROLE

Niels Refsgaard, Ishøj per Taastrup, Denmark, assignor to Dansk Designs Ltd., Mount Kisco, N.Y., a corporation of New York

Filed Aug. 29, 1966, Ser. No. 3,636

Term of patent 14 years

(Cl. D44—1)

FIG. 1

FIG. 2

FIG. 3

FIG. 4

FIG. 1 is a top plan view of a casserole embodying my new design;

FIG. 2 is a side elevational view thereof;

FIG. 3 is an end elevational view thereof; and

FIG. 4 is a partial sectional view taken along line 4—4 of FIG. 1.

I claim:

The ornamental design for a casserole, as shown.
